ELASTIC FLUID TURBINE ARRANGEMENT

Albert H. Buehman, Swampscott, Mass., assignor
to General Electric Company, a corporation of
New York

Application April 30, 1940, Serial No. 332,492

4 Claims.

(Cl. 60—1)

The present invention relates to elastic fluid turbine arrangements, more specifically to arrangements for turning the rotor of an elastic fluid turbine after the turbine has been shut down in order to assure uniform cooling of the rotor, thereby to prevent uneven expansion of the rotor shaft during the cooling period and to facilitate quick starting of the turbine.

The object of my invention is to provide an improved construction and arrangement of elastic fluid turbine turning mechanisms whereby a turbine rotor may be automatically turned at a low speed upon shut-down.

For a consideration of what I believe to be novel and my invention, attention is directed to the following description and the claims appended thereto in connection with the accompanying drawing.

In the drawing, Fig. 1 is a diagrammatic view of an elastic fluid turbine arrangement embodying my invention, and Fig. 2 is an enlarged, detail view of a part of Fig. 1.

The arrangement comprises an elastic fluid turbine 10 with an inlet conduit 11 including a stop or emergency valve 12 and a throttle valve 13. The throttle valve 13 is controlled by a speed governing mechanism in response to speed changes of the turbine. This speed governing mechanism comprises a speed governor 14 driven by a beveled gearing 15 from a shaft 16 secured to or forming part of the turbine rotor and supported by means including a turbine bearing 16a. Movement of the speed governor upon speed changes of the turbine rotor is transmitted to the throttle valve 13 by means including a hydraulic motor 17 and a pilot valve 18. The motor 17 has a piston 19 with a stem 20 connected to the left-hand end of a lever 21 which has an intermediate point held on a fulcrum 22 and a right-hand end pivotally connected to the throttle valve 13. The pilot valve 18 which like the motor 17 is of well known construction has valve heads secured to a stem 23 which is pivotally connected to an intermediate point of a floating and follow-up lever 24. The right-hand end of the lever 24 is pivotally connected to the piston stem 20 and the left-hand end of the lever 24 is pivotally connected to the speed governor 14. The pilot valve 18 is connected to the motor 17 by means including ports 25 and 26 normally covered by the pilot valve heads. Operating fluid under pressure such as oil is conducted to the pilot valve by a pipe 27 from a main source of supply.

During normal operation, with the stop valve

12 in open position, an increase in speed causes downward movement of the pilot valve heads whereby fluid under pressure is conducted to the lower side of the piston 19 and discharged from the upper side thereof, thereby causing upward movement of the piston 19. This effects closing movement of the throttle valve 13 and also upward movement of the pilot valve heads whereby the latter are restored to their normal position in which they cover the ports 25 and 26. During decrease in speed the operation of the speed-governing mechanism is similar except that the various elements move in opposite direction to effect opening movement of the valve 13.

During shut-down, for instance, with the stop valve 12 in closed position, the turbine rotor may be turned mechanically. The power agency for mechanically turning or rotating the turbine rotor in the present instance is in the form of an electric motor 28 connected by an electric circuit 29 to a source of electric energy 30. The circuit 29 includes contacts 31 bridged by a contact-making member 32 which is biased towards the contacts by a compression spring 33. Opening of the valve 12 effects movement of the contact-making member 32 away from the contacts 31 and likewise, closing of the valve 12 automatically causes closing of the contacts 31 by the action of the compression spring 33. Thus, opening and closing of the stop valve 12 automatically causes opening and closing respectively of the circuit 29 for the motor 28. The motor 28 which serves for rotating the turbine rotor, as will be more fully described hereinafter, also serves for driving an auxiliary pump 34 for supplying oil to the turbine bearing 16a and to the hydraulic motor during shut-down period and also upon failure of the main oil supply. The pump 34 which is driven from the shaft of the motor 28 has an inlet 35 for receiving oil and a discharge 36 connected by a pipe 31 to two pipes 38 and 39. The pipe 38 is connected with the turbine bearing and the pipe 39 is connected to the aforementioned conduit 27. The pipe 37 includes a check valve 40 and the pipe 27 includes another check valve 41 arranged ahead of the connection of the pipe 27 with the pipe 39 as regards the direction of flow of fluid from the main source of supply through the pipe 27. During normal operation of the turbine, oil is supplied from the main source through the pipe 27 to the pilot valve and the hydraulic motor and from the pipe 27 through the pipes 39, 38 to the turbine bearing 16a. During this condition the check

valve 40 prevents flow of oil from the pipe 39 into the pipe 37.

During operation of the turning motor 28 and the auxiliary oil pump 35, oil is supplied through the conduit 37 and the conduit 38 to the turbine bearing and from the conduit 37 through the conduit 39 to the hydraulic motor. During this condition, in which the turbine rotates at a low speed of the order of a few revolutions per minute, the piston 19 of the hydraulic motor is held in its lowermost position, thereby keeping the throttle valve 13 fully open and permitting quick starting of the turbine by opening of the stop valve 12.

Upon failure of the main source of oil supply, the motor 28 may be automatically started to maintain the oil supply to the bearing and the hydraulic motor by action of the auxiliary pump 34. The automatic starting of the motor 28 in response to failure of the main oil supply is accomplished by means including a pressure-responsive device in the form of a bellows 42 having an upper end connected by a pipe 43 to the pipe 27 ahead of the check valve 41 as regards the direction of flow of fluid from the main source of oil supply. The lower end of the bellows 42 carries a contact-making member 44 which, in the position shown, bridges two contacts 45 connected by wires 46 in parallel to the aforementioned contacts 31. As the oil pressure in the pipe 27 drops to a certain low value, the contacts 45 are closed, thereby bridging the contacts 31 and closing the circuit 29 of the motor 28 to effect operation of the auxiliary pump 34 and assuring the supply of oil or like operating fluid to the bearing and the hydraulic motor and other elements requiring fluid under pressure during operation. Thus, operation of the auxiliary oil supply pump may be automatically effected upon failure of the main oil supply by closing of the contacts 45, and also upon shutting down of the turbine by closing the stop valve 12.

During shut-down of the turbine, the turning motor 28 is automatically, mechanically coupled to the turbine shaft 16 as the speed of the turbine shaft drops to a predetermined low value. The arrangement for connecting and disconnecting the shaft of the motor 28 to the turbine shaft 16 includes a worm 47 driven from the turning motor 28 and engaging a gear 48 which is rotatably supported on a fixed shaft 49, Fig. 2. The shaft 49 is secured to a stationary support 50 by a pin 51. Axial movement of the gear 48 on the shaft 49 is limited by a washer 52 and a nut 53 secured to the shaft 49. A coupling or clutch half 54 of a tooth coupling is centrally arranged with and in the present instance integrally formed with the gear 48. Another half 55 of this coupling is supported on a splined shaft 56 aligned with and securely fastened to the shaft 16 by a connecting and supporting member 57. A compression spring 58 surrounding the splined shaft 56 and arranged between adjacent surfaces of the coupling half 55 and the connecting member 57 biases the coupling half 55 towards the left, that is, into engagement with the other coupling half 55. During normal turbine operation, that is, at high turbine speed, engagement of the coupling half is prevented by the action of two flyweights 59, 60 which are pivotally supported on the connecting and supporting member 57 and have arms or fingers 61 engaging the coupling half 55 to bias the latter towards the right, that is, away from the other coupling half 54, against

the spring 58 with a force which increases as the speed increases until the flyweights 59 and 60 rest against stops 62, thereby holding the coupling half 55 completely disengaged from the coupling half 54.

In the position shown in the drawing, the valve 12 is closed and the coupling or clutch 54, 55 is engaged, whereby the turning motor 28 rotates the turbine rotor at a low speed of the order of a few R. P. M. and also operates the pump 34 to supply oil to the bearing and the hydraulic motor as described above. If, now, the valve 12 is opened and elastic fluid is supplied to the turbine, the turbine rotor at first is driven by both the action of the elastic fluid and the motor 28. Due to the action of the elastic fluid supplied to the turbine, the rotor will begin to speed faster than the turning gear, and the teeth of the coupling half 55 will successively override the opposite teeth of the coupling half 54, alternately compressing the spring 58. This action takes place faster and faster as the turbine speed increases until, at the desired speed for which designed, the flyweights 59, 60 are forced out by the action of centrifugal force sufficiently to withdraw the coupling half 55 completely from the half 54. Thereupon, the turbine continues to operate entirely independently of the turning motor 28. If the stop valve 12 is sufficiently opened to effect opening of the contacts 31, the motor 28 is disconnected, provided that oil is supplied from the main source and the contact-making member 44 is held in opening position by the pressure-responsive device 42.

If the turbine is shut down, for instance by closing of the stop valve 12, the circuit of the motor 28 is closed. As the turbine speed drops to a value at which the flyweights will release the coupling half 55, allowing it to slide towards the coupling half 54 by action of the spring 58, the coupling will engage, though at first the coupling half 55 will override on the teeth of the coupling half 54. As the turbine speed has dropped to a speed equal to or slightly below the speed of the coupling half 54, the turbine rotor will be positively driven by the turning motor 28.

Though in general not desirable, the turbine may be operated, that is, started and stopped without the turning motor. The circuit of the latter may be disconnected from the line 30 by a switch 63.

The spring 58 is comparatively light, that is, only of a strength sufficient to overcome the sliding friction of the coupling half 55 on the splined shaft 56. With a light spring, the flyweights upon acceleration of the turbine rotor may throw out, that is, effect disengagement of the coupling at low speed. Also, each time the teeth of the coupling override as the turbine shaft overspeeds the turning gear, the coupling half 55 is forced against the spring 58, thereby assisting the flyweights 59, 60 in withdrawing the coupling half 55.

Thus, with my invention I have accomplished an improved construction and arrangement of turbine turning gear mechanisms which include a turning motor connected to the turbine shaft by means including a coupling or clutch having halves mechanically connected to the turning motor and the turbine shaft respectively, and mechanical means for effecting engagement and disengagement of the coupling in response to certain speed changes of the turbine. The turning motor of my invention may also drive an auxiliary oil pump for forcing oil to bearings and

to a hydraulic motor during operation of the turbine turning mechanism and also upon failure of the main oil supply. During turning operation the auxiliary oil pump supplying oil to the hydraulic motor holds such motor in a position in which the turbine throttle valve is held fully open, thereby permitting quick starting of the turbine by opening of a stop valve.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent of the United States is:

1. Elastic fluid turbine arrangement comprising a turbine having an inlet conduit with a stop valve and a throttle valve, a rotor with a shaft and a bearing for the shaft, a speed governing mechanism including a speed governor driven from the shaft and hydraulic means for moving the throttle valve in response to speed changes of the turbine, means normally supplying oil under pressure to the hydraulic mechanism, means including a turning motor for slowly rotating the turbine rotor upon shut-down, and means including a pump driven by the turning motor for supplying oil under pressure to the hydraulic mechanism and to the bearings upon shutdown of the turbine and upon failure of the main oil supply and a device responsive to oil pressure from the main oil supply automatically to effect starting of the turning motor as the pressure

of the main oil supply drops to a predetermined low value.

2. Elastic fluid turbine arrangement comprising a turbine having a rotor and an inlet conduit with a stop valve, and means for rotating the turbine rotor upon shut-down of the turbine, said means including a turning motor, an electric circuit for the motor including a contact-making device in cooperative relation with the stop valve automatically to close the circuit upon closing of the stop valve.

3. Elastic fluid turbine arrangement comprising a turbine having a rotor with a shaft, a bearing supporting the shaft and an inlet conduit with a stop valve and a throttle valve, means normally supplying oil under pressure to the bearing, means for rotating the turbine rotor upon shut-down, said means including a turning motor, an electric circuit for the motor including a contact-making device in cooperative relation with a stop valve automatically to close the circuit upon closing of the stop valve, means including an auxiliary oil pump driven by the turning motor to supply oil to the bearing during shut-down of the turbine and at the same time to maintain the throttle valve in open position to permit quick starting of the turbine.

4. Elastic fluid turbine arrangement comprising a turbine having a rotor and an inlet conduit with a valve, a motor for turning the rotor, and means including a device cooperatively associated with the valve for automatically starting the motor as the valve is moved into closing position.

ALBERT H. BUEHMAN.
